[57] ABSTRACT

A flashlight device for throwing light beams of different widths, and including a body which supports a light source for emitting light rays therefrom. A lens assembly is supported on the body for directing the light rays to form a light beam. The lens assembly includes a stationary lens disposed in the path of the light rays for directing the light rays in one direction and a movable lens for selective positioning in the path of the light rays to refract the light rays in another direction. More particularly, the lens assembly includes a hollow, sealed, compartment having a lens chamber disposed in the path of the light rays for receiving a fluid material to form a lens. A storage chamber is connected in fluid communication with the lens chamber for receiving the fluid from the lens chamber and removing the fluid material from the path of the light rays so that only the stationary lens is exposed to the light rays upon rotation of the body about the directional axis of the light beam.

VARIABLE-BEAM FLASHLIGHT DEVICE

BACKGROUND OF THE INVENTION

The present invention is related to flashlights, and more particularly, to flashlights which are capable of producing a light beam of variable intensity and size such that it may function either as a floodlight or a spotlight.

A flashlight which produces only a single beam is restricted in its use as the light rays which form the beam are either too concentrated and provide a high-intensity illumination over a small area or are so diffused as to provide a relatively lower intensity and illuminate a larger area. Therefore, it is desirable to provide a flashlight which can provide the concentrated, high-intensity light beam or the wide, low-intensity light beam whenever one or the other is required.

SUMMARY OF THE INVENTION

The present invention contemplates providing a flashlight device which is capable of producing a light beam of variable intensity such that it can function either as a spotlight or a floodlight for providing a high illumination of a small area or can illuminate a larger area when necessary. The flashlight device includes a body which has a light assembly mounted thereon which has a light source for producing light rays forming a light beam. A lens assembly is mounted on the body for gathering the light rays and directing them from the light source. The lens assembly includes one lens which is disposed in the path of the light rays which directs the light rays in one direction and another movable lens which is supported on the body for selective positioning in the path of the light rays for altering the direction of the light rays so that they will be directed in another direction. The lens assembly comprises a hollow, sealed compartment disposed adjacent the forward end of the body. The compartment includes a lens chamber disposed in the path of the light rays and a storage chamber offset with respect to the path of the light rays. The lens chamber is disposed in stationary relation with respect to the path of the light rays and is defined by spaced walls adapted to receive a fluid material therebetween. The storage chamber is connected in fluid communication with the lens chamber to enable the transfer of liquid material therebetween. The walls of the lens chamber are formed of a solid transparent material. In one form, one of the walls defines a stationary lens, and the liquid material, when disposed within the lens chamber, defines a movable or liquid lens. The storage chamber is connected adjacent only one side of the lens chamber so as to cause filling, by gravity, of the lens chamber when the storage chamber is positioned above the lens chamber, and emptying, by gravity, of the lens chamber when the storage chamber is positioned below the lens chamber. The storage chamber has a volume which is sufficiently large to enable liquid material to be emptied from the portion of the lens chamber which is disposed in the path of the light rays, and the volume of liquid material contained in the compartment is sufficient to fill that portion of the lens chamber which is disposed in the path of the light rays, such that all of the light rays produced by the light source will pass through the liquid material.

By the foregoing arrangement, when the body of the device is positioned in one position, for example, with the storage chamber disposed below the lens chamber, the light rays will pass through only the stationary lens and will be directed in one direction. On the other hand, when the body of the device is moved, such as rotated through approximately one-half turn, to position the storage chamber above the lens chamber, the liquid will flow from the storage chamber into the lens chamber and the light rays will pass through both the liquid lens and the stationary lens to alter the direction of the light rays from their direction when passing only through the stationary lens. Such an arrangement enables the light rays to be controlled such that the light rays concentrated to produce a narrow, high-intensity light beam to function as a spotlight or are diffused to produce a wider, low-intensity light beam to function as a floodlight.

BRIEF DESCRIPTION OF THE DRAWINGS

FIG. 1 is a perspective view of the flashlight device of the present invention;

FIG. 2 is a fragmentary, partially in section, side elevation view of the flashlight device shown in FIG. 1;

FIG. 3 is a side elevation view of the same portion of the flashlight device shown in FIG. 2, when rotated one-half turn;

FIG. 4 is a fragmentary, partially in section, side elevation view of another embodiment of the present invention;

FIG. 5 is a view of the same portion of the flashlight device shown in FIG. 4 when rotated one-half turn;

FIG. 6 is a fragmentary, partially in section, side elevation view of still another embodiment of the flashlight device of the present invention;

FIG. 7 is a view of the same portion of the flashlight device as shown in FIG. 6 when rotated one-half turn;

FIG. 8 is a fragmentary, partially in section, side elevation view of a further embodiment of the present invention; and

FIG. 9 is a view of the same portion of the flashlight device shown in FIG. 8 when rotated one-half turn.

DESCRIPTION OF THE PREFERRED EMBODIMENTS

The flashlight device of the present invention is illustrated, generally at 2, in FIGS. 1 to 3, and as shown, includes a body 4 having a head portion 6 at one end, such as the front end, and a grip portion 8 in the opposite or rear end. As shown, particularly in FIG. 2, the lightassembly 10 is mounted in the head portion 6 and includes a light source, such as a light bulb 12, adapted to produce light rays, as at 14, which form a light beam 16. A reflector assembly 18 is mounted within the head portion 6 and surrounds the bulb 12 being angled upwardly and forwardly therefrom, such that the light rays 14 are directed generally forwardly away from the device.

Although the body 4 may be of any general configuration, the grip portion 8 is of a generally conventional construction being provided in the form of a hollow, elongated cylinder which is adapted for supporting one or more batteries (FIG. 2), for energizing the bulb 12. A conventional switch assembly (not shown) may be supported interiorly of the grip portion 8 and may include a slide contact 21 (FIG. 1) for selectively energ-

gizing and de-energizing the bulb 12 in a manner well-known to the art.

A selectively positionable lens assembly 24 is supported adjacent the front end of the head portion 6 which is positionable for altering or changing the direction of the light rays, and thus, the size and intensity of the light beam 16. More particularly, the lens assembly 24 includes a movable lens, such as at 28, which is positionable in one position in the path of the light rays 14 when the body is disposed in one position, such as illustrated in FIG. 2, and is positionable out of the path of the light rays 14 when the body is rotated one-half turn or 180°. By this arrangement, the lens 28 acts on the light rays to produce, in one instance, a wide-low-intensity beam or floodlight and in another instance, a narrow, high-intensity beam or spotlight.

Referring now particularly to FIG. 2, the lens assembly 24 comprises a hollow sealed compartment 26, and the movable lens 28 comprises a fluid material, such as a liquid or the like, which is disposed within the compartment 26. In the form shown in FIG. 2, the reflector assembly 18 is positioned behind the compartment 26 and includes a reflector member 19. The reflector 19 may be of any suitable configuration, but in the form shown is of a generally paraboloid-shape having the bulb 12 located at the focus thereof for forming the light rays 14 into the beam 16 which passes through the compartment 16. The compartment 26 includes one chamber or lens chamber 30 which is disposed in the path of the light rays, and another chamber or storage chamber 32 which is offset from the path of the light rays 14 and which is connected in fluid communication, as at 33, with the lens chamber 30 to enable the liquid to be transferred between the lens chamber 30 and the storage chamber 32 when the body 4 is rotated, as aforesaid. In FIGS. 2 and 3, the compartment 26 is made of a solid, transparent material, such as plastic or the like, and is defined in cross section adjacent the lens chamber 30 by laterally extending, spaced front 40 and rear walls 35 and 36, respectively. Although this compartment 26 may be formed in many suitable configurations, in the form shown in FIGS. 2 and 3 the rear wall 36 is foreshortened with respect to the front wall 35, such that the upper end of the front wall defines a front wall for the storage chamber 32. The storage chamber 32 is further defined in cross section by a bottom wall 37 which is integrally formed with the upper end of the rear wall 36 and extends rearwardly therefrom. An upper rear wall 38 is formed integrally with the rear end of the bottom wall 37 and extends upwardly therefrom in laterally-spaced relation with respect to the upper end of the front wall 35 providing the storage chamber with a greater transverse dimension from front to rear than the lens chamber 30. A top wall 40 and peripheral side wall 41 are integrally joined to the peripheral edges of the front wall 35, the rear walls 36 and 38 and the bottom wall 37 to complete the sealing off of the compartment 26. As shown in FIG. 1, the chamber 32 is connected to the chamber 30 adjacent only one side thereof, such that when the chamber 32 is disposed above the chamber 30, the liquid 28 will drain, by gravity into the chamber 30, whereas, when the body is rotated one-half turn or 180° about the directional axis of the light beam, and the chamber 32 is disposed below the chamber 30, the liquid 28 will drain, by gravity, into the chamber 32.

In the form shown in FIGS. 2 and 3, the liquid lens 28 is preferably of a clear or transparent material, such as water or the like, and is provided in a volume which substantially fills the chamber 30 up to the upper end 5 of the rear wall 36. The transverse dimensions of the front wall 35 and rear wall 36 are greater in all directions than the corresponding dimensions of the front edge 39 of the reflector 19, so that all of the light rays 14 will be directed through the liquid lens 28 when 10 such is disposed in the chamber 30. By this arrangement, the liquid lens 28 acts in conjunction with the front wall 35 to alter the direction of the light rays 14 as they pass therethrough, that is, alter the direction of the light rays from the direction they would normally 15 take when passing through only the front wall 35 when the liquid is not disposed in their path.

In the form shown in FIGS. 2 and 3, the portion of the front wall 35 adjacent the chamber 30 is formed in a series of superposed, concavo-convex domes 44. The 20 domes 44 are convex adjacent the front surface 45 and concave adjacent the rear surface 46 so as to form a refracting lens in conjunction with the liquid 28 such that the light rays 14 will be diffused to form a wide, low-intensity beam 16. As shown in FIG. 3, when the chamber 30 is empty, the light rays 14 will pass in a straight line through the chamber 30 and the front wall 35 to form a narrow, high-intensity beam 16b.

In another embodiment of the present invention, as 30 shown in FIGS. 4 and 5, a front wall 35a is provided which has generally flat front 45a and rear 46a surfaces. In this form, the chamber 30 is preferably filled with a translucent liquid, such as an aqueous suspension of starch or the like, so that the liquid rays 14 will be diffused by virtue of the translucency of the liquid 35 to form a wide, low-intensity beam 16c as seen in FIG. 4. To the contrary, when the liquid 28 is emptied from the chamber 30, as shown in FIG. 5, the light rays 14 will pass in a straight line through the chamber 30 and the front wall 35a to form a narrow, high-intensity beam 16d.

In the embodiment of the invention shown in FIGS. 6 and 7, a front wall 35b adjacent the chamber 30 has a prismatic interior surface formed by a plurality of light dispersing lenses, such as transversely extending prisms 50. In this form, the material of the front wall 35b and the liquid 28 have a refractive index which is generally identical such that when the chamber 30 is empty, as in FIG. 6, the light rays 14 will be diffused by the prisms 50 to form a wide, low-intensity beam 16. On the other hand, when the liquid 28 is disposed in the chamber 30, the combined refractive characteristics of the liquid 28 and the prisms 50 are such as to cause the light rays 14 to pass in a straight line to form a narrow, high-intensity beam 16f, as in FIG. 7.

There is illustrated in FIGS. 8 and 9 another embodiment of the present invention. In this form, a lens assembly 60 is provided which includes a sealed compartment 62 having a lens chamber 64 and a storage chamber 66. The lens chamber 64 and storage chamber 66 are connected in fluid communication with one another by apertures, as at 68, to enable liquid 70 to pass therebetween.

In this form, the lens chamber 64 is defined by a rear wall 72 and a front wall 74 which is disposed inferiorly of the rear wall 72. The rear wall 72 is shown as being generally paraboloid-shaped in configuration and surrounds the bulb 12 which is disposed at the focus

thereof. The front wall 76 is shown as being generally conical-shaped in configuration and also surrounds the bulb 12. More particularly, the rear wall includes a generally, centrally located bore 82, and the front wall 76 includes a cylindrical hub 84 adjacent its apex which is form-fitted in sealing engagement within the bore 82, defining a socket 85 for receiving the contact end 88 of the bulb 12. The front wall 76 extends forwardly and has its forward edge 78 joined in sealing engagement adjacent the lens chamber 64 for receiving a fluid material, such as an opaque or translucent liquid 70 therein. A generally flat or planar cover plate 77 of transparent material is mounted over the open end of the front wall 76.

As further shown in FIG. 8, the storage chamber 66 is defined by a front wall 90 which extends upwardly from the front edge of the rear wall 72 and a rear wall 92 which is integrally joined with the rear wall 72 in laterally spaced relation from the front wall 90. An outer peripheral side wall is integrally joined to the upper edges of the front wall and rear wall 92 of the storage chamber 66 for sealing the compartment 62. As can be seen, the apertures 68 are disposed between the front wall 90 and the rear wall 92 such that the liquid 70 may pass back and forth between the lens chamber 64 and the storage chamber 66 upon rotation of the body 9 through one-half turn or 180° as shown in FIG. 9.

Referring now particularly to FIG. 9, the rear wall 72 may be made of any suitable material such that its interior side or surface 96 has reflective characteristics, and thus, will act as a reflector under certain conditions as will be described hereinafter. The front wall 76 is made of a transparent material such that the light rays 14 emitted from the light bulb 12 will pass therethrough for reflection off of the interior side 96 of the rear wall 72 to form a narrow, high-intensity light beam 16g. As stated, the front wall 76 surrounds the light bulb 12 and extends angularly, forwardly and upwardly therefrom, being disposed at an angle, such as approximately 45° with respect to the directional axis of the light beam, such as 16g, such that when the liquid 70 is disposed within the lens chamber 64, the combined refractive characteristics of the liquid 70 and front wall 76 are such that a substantial portion of the light rays will be reflected without penetrating the liquid 70, or will be refracted by the liquid in lens chamber 64 to alter the direction of the light rays 14 reflected from the rear wall 72 to form a wide, low-intensity beam, such as at 16h.

I claim:

1. A flashlight device for producing a light beam of variable width and intensity comprising, a body, a light assembly including a light source mounted on said body for directing light rays in generally one direction from said light source to produce a light beam, lens means supported by said body for selectively altering the direction of said light rays, said lens means comprising a hollow sealed compartment having a transparent fluid therein, said compartment including a transparent lens chamber for receiving a fluid material therein, and a fluid storage chamber for storing said fluid when it is not disposed in said lens chamber, said lens chamber being mounted in the path of said light rays and defining when empty a solid lens for

causing said light rays to form a beam of one width and one intensity, said fluid storage means being mounted out of the path of said light rays and connected in fluid communication with said lens chamber to enable selective transfer of said fluid material between said fluid storage chamber and said lens chamber, and said fluid material defining a movable lens when disposed in said lens chamber and co-acting with said solid lens to cause said light rays to form a beam having another width and another intensity.

2. A device in accordance with claim 1, wherein said lens chamber is mounted in substantially stationary relation on said body.

3. A device in accordance with claim 1, wherein said lens chamber is connected at only one side to said storage chamber to enable said fluid to fill said lens chamber, by gravity, when said storage chamber is positioned above said lens chamber and to enable said fluid to be emptied from said lens chamber, by gravity, when said storage chamber is positioned below said lens chamber upon rotation of said body 180° about the directional axis of said light beam.

4. A device in accordance with claim 1, wherein said storage chamber has a volume sufficiently large to enable said lens chamber to be completely emptied of fluid.

5. A device in accordance with claim 1, wherein said lens chamber is defined by a front wall and rear wall spaced from said front wall, and said fluid storage is connected in fluid communication with said lens chamber for filling the space between said front and rear walls.

6. A device in accordance with claim 5, wherein said front and rear walls are disposed radially outwardly of said light source, and said fluid forms a lens for reflecting said light rays when disposed within said lens chamber.

7. A device in accordance with claim 5, wherein said front and rear walls are disposed forwardly of said light source, and said fluid forms a lens for the passage of said light rays therethrough when disposed within said lens chamber.

8. A device in accordance with claim 5, wherein said front and rear walls are disposed radially outwardly of said light source, and said fluid forms a lens for reflecting said light rays when disposed within said lens chamber.

9. A device in accordance with claim 5, wherein said lens means includes a reflector surrounding said light source, and said reflector extends outwardly and forwardly of said light source for directing said light rays forwardly away from said light source.

10. A device in accordance with claim 9, wherein said reflector is disposed rearwardly of said front and rear walls for reflecting said light forwardly through said one chamber.

11. A device in accordance with claim 5, wherein said front wall extends angularly outwardly and forwardly from said light source, and said fluid forms a lens for reflecting said light rays forwardly away from said light source.

12. A device in accordance with claim 5, wherein said front wall comprises a diffusing lens for diffusing

said light rays when said space is filled with fluid.
 13. A device in accordance with claim 5, wherein
 said front wall comprises a diffusing lens for diffusing
 said light rays when said space between said walls
 is not filled with fluid.

14. A flashlight device for producing a light beam of
 variable width and intensity comprising,
 a body,
 a light assembly including a light source mounted on
 said body for directing light rays in generally one 10
 direction from said light source to produce a light
 beam,
 lens means supported by said body for selectively al-
 tering the direction of said light rays,
 said lens means comprising a hollow-sealed compart- 15
 ment having a fluid therein,
 said compartment including a transparent lens cham-
 ber for receiving a fluid material therein, and
 a fluid storage chamber for storing said fluid when it
 is not disposed in said lens chamber,
 20 said storage chamber has a volume sufficiently large

to enable said lens chamber to be substantially
 emptied into said storage chamber,
 said lens chamber being mounted in the path of said
 light rays and defining when empty a solid lens for
 causing said light rays to form a beam of one width
 and one intensity,
 said storage means being mounted out of the path of
 said light rays and connected in fluid communication
 at only one side to said lens chamber to enable
 said fluid to fill said lens chamber, by gravity, when
 said storage chamber is positioned above said lens
 chamber and to enable said fluid to be emptied
 from said lens chamber, by gravity, when said stor-
 age chamber is positioned below said lens chamber
 upon rotation of said body 180° about the direc-
 tional axis of said light beam, and
 said fluid material defining a movable lens when dis-
 posed in said lens chamber and coating with said
 solid lens to cause said light rays to form a beam
 having another width and another intensity.

* * * * *
